[57] CLAIM

The ornamental design for wine selector, as shown and described.

DESCRIPTION

FIG. 1 is a top plan view of a wine selector showing my new design;

FIG. 2 is a front elevational view, the opposite side being a mirror image thereof; and

FIG. 3 is a left side elevational view, the opposite side being a mirror image thereof.

The undisclosed bottom surface is conventionally flat and unornamented.
